United States Patent Office

Des. 183,607

Patented Sept. 30, 1958

183,607

CHAIR

Henry P. Glass, Chicago, Ill., assignor to Astra Bent
Wood Furniture Company, New York, N. Y.

Application December 26, 1957, Serial No. 49,030

Term of patent 3½ years

(Cl. D15—1)

FIG. 1.

FIG. 2.

Fig. 1 is a front perspective view of my ornamental design for a chair looking at the right front corner; and

Fig. 2 is a rear perspective view of the chair looking at the right rear corner.

I claim:

The ornamental design for a chair, substantially as shown.
